Primary Examiner — Nathaniel D. Buckner*(74) Attorney, Agent, or Firm* — Kirk A. Buhler; Buhler & Associates Patenting(57) **CLAIM**

The ornamental design for a corner rounder jig, as shown and described.

DESCRIPTION

FIG. 1 is a top perspective view for a corner rounder jig showing my new design;
FIG. 2 is a top plan view thereof;
FIG. 3 is a bottom view thereof;
FIG. 4 is a rear elevation view thereof;
FIG. 5 is a front elevation view thereof;
FIG. 6 is a right side elevation view, the left side elevation view being a mirror image thereof;
FIG. 7 is a bottom perspective view thereof; and,
FIG. 8 is a top perspective view in an environment of use. The broken lines in FIG. 8 depict environmental subject matter and form no part of the claimed design.
